F. LE R. SATTERLEE

COIL MOUNTING

Filed May 13, 1922

Francis Le Roy Satterlee ^{INVENTOR}
BY his ATTORNEY, Darby & Darby

UNITED STATES PATENT OFFICE.

FRANCIS LE ROY SATTERLEE, OF FLUSHING, NEW YORK.

COIL MOUNTING.

Application filed May 13, 1922. Serial No. 560,737.

This invention relates to coil mountings, and is more particularly directed to such type of mountings that are commonly employed in radio signalling for supporting or having mounted thereon inductance coils.

The object of the invention is to provide a mounting of this character which is simple in structure, efficient in operation, and economical of manufacture.

10 A further object of the invention is to provide a mounting of this type wherein maximum efficiency and variation in coupling between inductance coils may be secured.

15 A further object of the invention is to provide in a mounting of this type means whereby any type of inductance coils may be most efficiently positioned with reference to each other, and wherein the most efficient coupling between the circuits in which 20 the coils are included may be effected.

Further objects of the invention will appear more fully hereinafter.

The invention consists substantially in the 25 construction, combination, location, and relative arrangement of parts, all as will be more fully hereinafter set forth, as shown in the accompanying drawing, and finally pointed out in the appended claims.

30 Referring to the drawing:—

Fig. 1 is a plan view of one type of coil mounting embodying my invention.

Fig. 2 is a sectional view taken on the line 2, 2, Fig. 1, looking in the direction of 35 the arrows.

Fig. 3 is a sectional view taken on the line 3, 3, Fig. 2, looking in the direction of the arrows.

The same part is designated by the same 40 reference numeral wherever it occurs throughout the several views.

Where a loose coupling is desired between the inductance coils, and especially in the radio art, it is customary to vary the position of the coils relative to each other by hand, moving one coil relative to the other, and rely on the weight of the coils to prevent further movement. This movement is unsatisfactory in that a jar to the panel supporting coils, or the table on which the coils are laid, frequently cause the adjustment thereof to become disturbed. Further, a fine adjustment or space between the inductance coils frequently required, especially 45 in radio work, is difficult to obtain in this manner. With the advent of the type of coils

known as honeycomb coils, duo-lateral coils, spider web coils, or the like, held by a mounting, it became the practice to employ in connection with these coils a standard type of 60 mounting wherein one coil, usually the center coil, was held rigidly by the mounting or support, and the other coil or coils, if more than two coils were employed, were supported by the mounting for pivotal move- 65

ment relative to the fixed coil. I have found that the most efficient results are obtained when the fixed coil can be moved vertically or laterally, as the case may be, relative to the pivotal coils. In other words, for ex- 70

ample, in the case of a three coil mounting, where the center coil is fixed and the two side coils are pivotally supported, when the proper pivoted position of the pivotally sup- 75

ported coils is effected, great advantage is obtained in being able to move the fixed coil, that is, fixed so far as pivotal movement is concerned, relative to the pivoted coils in a straight line or plane as distinguished from pivotal movement. I will now describe a 80 structure which secures the advantages of such an arrangement and is capable of the foregoing operation. I have shown, and will describe the structure as a triple coil mounting, but I wish it to be understood that I do 85

not desire to be limited or restricted in this respect, as two or more coils may be employed and embody the features of my invention. Furthermore, I have shown for the purpose of illustration, a honeycomb or duo- 90

lateral type of coil, but I do not desire to be limited or restricted in this respect, for any

type of inductance coil commonly employed in the radio art, such as either of the two mentioned, or the so-called spider web coil, 95

etc., may be employed.

Referring to the drawing: I have shown a coil mounting structure adapted for connection to a vertical type of panel board. Obviously I do not desire to be limited to 100 any particular type as by mere matter of design the structure may be supported by a standard or adapted to be connected to the horizontal type of panel. The support consists of the back 1. The back or base 1 has 105 secured thereto two frame members 2 and 3, spaced from each other. The frame members 2 and 3 form a support for shafts 4 and 5, which, in turn, support socket blocks 7 and 6. These blocks contain plug and 110 jack arrangements in the form selected for illustration for attachment to similar plug

and jack blocks carried by the inductance coils in the manner now well known in the art, for example, as shown in Letters Patent No. 1,365,170, January 11, 1921, to R. F. Gowen. The inductance coil is illustrated at 8, and the block thereof at 9. In the manner illustrated in the Gowen patent above identified, the shafts 4 and 5 are each provided with a gear wheel 10, generally located underneath the frame 3, which mesh with gear wheels 11, carried by shafts 12, the movement of which is controlled by handles 13. By this arrangement it will readily be seen that by rotating handles 13, shafts 4 and 5 may be rotated, and thus pivotal movement imparted to the respective coils 8. The foregoing structure forms no part of my present invention, and the standard type employed in the art today as illustrated in the Gowen patent above identified has been selected for the purpose of illustration of the invention here involved. My invention has for its object the adjustment of the coil, which hitherto has been unadjustable, and the adjustment is a linear adjustment rather than a pivotal one. In accordance with my invention I dovetail the frames 2 and 3, and provide the usual plug and socket block 14, likewise dovetailed, to form a dovetailed sliding connection in the frames 2 and 3. A coil 8 may, in a manner similar to blocks 7, be plugged into the block 14. The block 14, however, is provided with gear teeth 15, which are in mesh with a worm 16, carried by shaft 17, supported by the frame members 2 and 3, which shaft 17 is adapted to be rotated by knob 18. From the foregoing it will be apparent that by rotation of the knob 18, the block 14, and in consequence the coils supported thereby, may be moved, in this instance, vertically, without varying the lateral adjustment between the coils 8. In this manner a most efficient positioning of the intermediate coil, or the so-called fixed coil, may be secured, and the elements of coupling most efficient for any particular value or design of coil may be thus obtained. While I have shown and described the foregoing structure as illustrative of the invention, I wish it to be understood that I do not desire to be limited or restricted to the details of structure

thereof, as many modifications and changes in the details will readily occur to those skilled in the art without departing from the spirit and scope of my invention as defined in the claims. 55

Having now set forth the object and nature of my invention, however, and having shown and described one practical structure embodying the principles thereof, what I claim as new and useful and of my own invention and desire to secure by Letters Patent is,—

1. In an inductance coil mounting, the combination with a support, of a rotatable member carried by said support, of a second member positioned adjacent said rotatable member, means for moving said second member in a plane parallel to the axis of rotation of said rotatable member, means for securing inductance coils to said members to form rigid units therewith. 65

2. In an inductance coil mounting, the combination with a support, of an inductance coil pivotally carried by said support, a second coil carried by said support, and means for moving said second coil in said support linearly in a plane parallel to the axis of pivotal movement of the first mentioned coil. 75

3. In an inductance coil mounting, the combination with a support, of a plurality of coils carried by said support, means for imparting pivotal movement to said coils independently of each other, an associated coil also carried by said support, and means for imparting linear movement to said associated coil. 85

4. In an inductance coil mounting, the combination with a support, of an inductance coil pivotally carried by said support, a second coil carried by said support, and means for moving said second coil in said support linearly in a plane parallel to the axis of pivotal movement of the first mentioned coil, and independent manually operated means for moving said first mentioned coil. 90

In testimony whereof I have hereunto set my hand on this fifth day of May A. D., 1922. 100

FRANCIS LE ROY SATTERLEE.
